F. H. BULLINGER

RHEOSTAT

Original Filed June 28, 1924

Fig. 1.

UNITED STATES PATENT OFFICE.

FREDERIC H. BULLINGER, OF YONKERS, NEW YORK, ASSIGNOR TO LULA M. PURVIANCE, OF LOS ANGELES, CALIFORNIA.

RHEOSTAT.

Application filed June 28, 1924, Serial No. 722,962. Renewed December 23, 1925.

To all whom it may concern:

Be it known that I, FREDERIC H. BULLINGER, a citizen of the United States, residing at Yonkers, in the county of Westchester 5 and the State of New York, have invented a certain new and useful Improvement in Rheostats, of which the following is a full, clear, concise, and exact description.

My invention relates to rheostats and 10 sides in a construction rendering it especially useful in automobile equipment, the rheostat of my invention being adapted for assembly adjacent or on the steering hand wheel. The rheostat of my invention is, 15 however, not to be limited to any particular use. My rheostat includes a hollow casing, two bearings, one at each end of the casing, a shaft mounted to turn in said bearings, a sectional resistance carried by and turning 20 with said shaft and disposed between said bearings, a switch block between said bearings and also carried by said shaft adjacent one of said bearings, a row of contacts that are connected with different sections of the 25 resistance and adjacent one of said bearings, a stationary contacting element engageable with said contacts, and a handle connected with the shaft at the other end of the casing and upon the exterior thereof.

30 The invention will be more fully explained in connection with the accompanying drawing illustrating the preferred embodiment thereof and one of its uses. In the drawing, Fig. 1 shows the rheostat of my invention assembled with the steering column of an automobile, this figure also illustrating the head lamps of an automobile in whose circuit the rheostat is included to control the brilliance of the illumination 35 furnished by these lamps; Fig. 2 is a view illustrating the casing and a portion of the mounting for the casing in section, the rheostat itself being shown in elevation; Fig. 3 is a sectional view on line 3—3 of 40 Fig. 2; Fig. 4 is a sectional view on line 4—4 of Fig. 2, the resistance sections being diagrammatically indicated; and Fig. 5 is a sectional view on line 5—5 of Fig. 2.

The rheostat is contained within a hollow 45 casing 1 which is preferably tubular and which may be clamped upon the steering column or other supporting device in any suitable way, as by means of the clamps 2, of any suitable construction. The casing includes caps 3, 4 which are assembled with

the body of the casing by means of the screws 5. A bearing 6 is secured to the outer end of the cap 3, this bearing having an annular recess 7 which receives the cap end. Another bearing 8, preferably of insulation, is secured to the cap 4 by means of the screws 9. The bearings are thus at opposite ends of the casing. The conductors 10 and 11 pass into the casing cap 4 and are fastened to the outer flat face of the bearing 8 by means of bolts 12 and 13 which pass through the bearing block 8. The stationary spring contact arms 14 and 15 are clamped, each at one end, against the inner flat face of the bearing 8. A shaft 16 passes between the switch arms 14 and 15 and is mounted to turn in the bearings 6 and 8. This shaft carries the sectional resistance 17, which may be of any suitable form, resistance wire being illustrated as an example. 55 A switch block 18, also preferably of illustration, carries an arcuate row of contacts 19, 20, 21, 22, 23 which face the bearing 8 and the switch arms 14, 15, the contacts 19 and 23 being connected with the extreme ends of the resistance as a whole and the contacts 20, 21, 22 being connected with terminals of sections of the resistance as diagrammatically indicated in Fig. 4. The contact 23 is elongated sufficiently to be constantly engaged by the switch arm 15. The contact 14 is successively engageable with the contacts. A handle 24 is connected with the shaft 16 adjacent the bearing 6 and upon the exterior of the hollow casing. 60

In operation the entire resistance unit together with the switch contacts that are connected with its terminals and with the different sections of the resistance, as hereto set forth, are rotated to move the contacts 65 successively into engagement with the stationary switch arm 14 while contact 23 is in engagement with the switch arm 15. The rheostat of my construction may be readily formed in separate parts which are capable 70 of easy assembly and the wiring is much simplified as compared with other rheostats capable of like use.

I claim:

1. The combination with a hollow casing 75 having a removable cap at one end; of a bearing within the casing at the other end thereof; a shaft surrounded by the casing and having one end journaled in said bearing and its other end journaled in said cap; 80

a handle upon the exterior of the casing and connected with the latter end of the shaft; a sectional resistance within the casing and disposed between said bearing and handle, 5 said resistance being carried by and turning with the shaft; a contact carrier disposed between said sectional resistance and bearing, this carrier being supported by and turning with the shaft; a row of contacts 10 upon the carrier and individually connected with the different resistance sections, these contacts having contacting ends facing said bearing; and switch arms carried by the bearing and having engagement with said 15 contacts successively as the handle is turned.

2. The combination with a hollow casing having a removable cap at one end; of a bearing within the casing at the other end thereof; a shaft surrounded by the casing 20 and having one end journaled in said bearing and its other end journaled in said cap; a handle upon the exterior of the casing and connected with the latter end of the shaft; a sectional resistance within the casing and disposed between said bearing and handle, 25 said resistance being carried by and turning with the shaft; a contact carrier disposed between said sectional resistance and bearing, this carrier being supported by and turning with the shaft; a row of contacts 30 upon the carrier and individually connected with the different resistance sections, these contacts having contacting ends facing said bearing; and a contacting structure carried 35 by the bearing and having engagement with said contacts successively as the handle is turned.

3. The combination with a hollow casing having a removable cap at one end; of a bearing within the casing at the other end thereof; a shaft surrounded by the casing 40

and having one end journaled in said bearing and its other end journaled in said cap, a handle upon the exterior of the casing and connected with the latter end of the shaft; a sectional resistance within the casing and disposed between said bearing and handle, 45 said resistance being carried by and turning with the shaft; a contact carrier disposed between said handle and bearing, this carrier being supported by and turning with the shaft; a row of contacts upon the carrier and individually connected with the different resistance sections, these contacts having contacting ends facing said bearing; and switch arms carried by the bearing and having engagement with said contacts successively as the handle is turned. 50

4. The combination with a hollow casing having a removable cap at one end; of a bearing within the casing at the other end thereof; a shaft surrounded by the casing and having one end journaled in said bearing and its other end journaled in said cap; a handle upon the exterior of the casing and connected with the latter end of the shaft; a sectional resistance within the casing and disposed between said bearing and handle, 55 said resistance being carried by and turning with the shaft; a contact carrier disposed between said handle and bearing, this carrier being supported by and turning with the shaft; a row of contacts upon the carrier and individually connected with the different resistance sections, these contacts having contacting ends facing said bearing; and a contacting structure carried by the bearing and having engagement with said contacts successively as the handle is turned. 60

In witness whereof, I hereunto subscribe my name.

FREDERIC H. BULLINGER.
